HEATING APPARATUS.

James M. Cripps, Wharton, Tex., assignor to
Danciger Oil & Refining Company, Fort Worth,
Tex., a corporation of Texas

Application January 10, 1946, Serial No. 640,354

3 Claims. (Cl. 263—20)

1

This invention relates to an improved heating apparatus, more particularly to an improved heating coil structure.

In the arts there are many processes in which it is desired to heat fluids, such as gases, to high temperatures. Heretofore, gases have been heated in furnaces equipped with pipes or tubes connected with return bends to form a continuous coil. Such tubes have been fabricated of iron and its alloys particularly the heat resistant chromium and nickel-containing alloys. An essential limiting factor in thermal processes utilizing such tubes is the temperature at which the alloys soften or deform. As a general rule such limiting temperature is of the order of 1800° F. when the relatively available ferrous alloys are used. When temperatures substantially above this are involved other types of material must be used.

In processes involved the heating of gases to temperatures substantially above 1800° C. tube structures of high melting point metals, such as molybdenum and tungsten have been suggested and employed. However, these metals are quite expensive not only because of their relative scarcity but also because of the difficulty in fabricating these metals into the ultimate desired shapes; furthermore, these metals also have properties that prevent their economic use in continuous heating of gases to high temperatures.

The more commonly used structure for heating gases to temperatures above about 1800° F. consist of regenerative furnaces constructed of checker-work of refractory ceramics. High temperatures may be attained in this type of furnace. The operation of this type of furnace, as is known, is not particularly efficient. As is known, these operate on a cyclic principle, i. e., the flow of gas therethrough must be periodically stopped or diverted to permit heating up of the checker-work. Even when employed in batteries such furnaces are not too desirable because the diversion and variation in flow and temperature is reflected in undesired variations in the products discharged from the furnace. Such variations usually complicate the treatment of the gas following the heating. Furthermore, furnaces of this type require a number of expensive valves that must operate efficiently at high temperature in order properly to control the alternate introduction of air and gas into the furnace and their discharge from the furnace through separate channels.

It has been found that gases may be highly

2

heated and continuously over long periods of time in a most economical manner. This may be accomplished by passing the gas to be heated through an externally heated coil composed of a series of tubes and return bends constructed of suitable refractories.

In order to enable a more ready comprehension of the invention there is shown in the accompanying drawing a typical physical embodiment of the invention in which

Fig. 1 is a diagrammatic illustration of a furnace in which the improved continuous coil structure is mounted; and

Fig. 2 is an enlarged vertical sectional detail of the return bend and associated tube sections which conjointly form a coil.

It has been found, as is described in the co-pending application of Otto Spring, Serial No. 540,385, filed June 15, 1944, now Patent No. 2,466,617, that gases may be heated to high temperatures of the order of 2500° F. to 3000° F. by passing the gas through a specially constructed refractory coil, the exterior of which is exposed to hot combustion gases. As there disclosed, such a continuous coil may be mounted within a fired furnace and such coil was established by associating tubes of suitable refractory material such as "Carbofrax" (silicon carbide) with return bends formed of the same material. The lower return bends were positioned on the floor of the furnace and the associated tubes extended vertically from the lower to the upper return bends. In this way the tubes were wholly supported on the furnace floor. The upper return bends were spaced somewhat below the roof of the furnace so that the tubes were free to expand and contract in a vertical direction with change in temperature in the furnace. In operation, gases to be heated were passed through the coil while the exterior of the coil was exposed to hot combustion gases in the furnace. With such a refractory coil gases may be heated to temperatures of 2500° F. to 3000° F.

In such prior coil construction the return bends were each molded in two symmetrical portions and after baking the two sections were cemented together. This provided a return bend in which the joint or seam between the sections was in the vertical axis or plane of the tube section of the coil. In installing the coil in a furnace the tubular units were inserted in recesses in the return bends and sealed by means of a suitable cement.

It was learned that in commercial use of such a coil certain undesirable effects developed. It

was found that after a certain period of operation, varying between one week and several months, gas began to leak from the coil. Upon examination it was ascertained that this was due to a slit or fissure which formed in the return bends. This crack or slit was generally coincident with the seams and was due to the breakdown of the cement joint. The fault could be temporarily remedied by applying cement to the seams. However, after some additional time of operation the seams again opened and the cementing had to be repeated. This, of course, involved a considerable loss in time for shut down and repair. Such repairing furthermore was not complete due to the fact that the portion of the slit contiguous the furnace floor could not be reached and thus remained an open leak.

After considerable experimentation and trials it was found that the difficulty could be practically obviated to insure marked longevity in the coil by forming the sections of the return bends so that the contiguous faces or the joint between the sections are in a horizontal plane, i. e., parallel to the floor of the furnace. This structure proved to be as efficacious as it was simple.

The improved coil structure and its operation can be more readily comprehended from a consideration of a simplified embodiment depicted in the accompanying drawings.

As there shown, the coil, designated generally by the letter C, is positioned in any suitable type of furnace. Such furnace may, for example comprise a floor 1, end walls 2, side walls, not shown, roof 3 and the stack 4. The furnace may be fired by any suitable means such as the burner 5. A bridge wall 6 may or may not be utilized in the furnace structure.

The coil C preferably is constructed of a suitable refractory material, such as Carbofrax (silicon carbide) and is made up of the tubular units 7 and the return bends 8. The tubes 7 and return bends preferably are of standard shape and are therefore readily interchangeable and replaceable. The tubes may be of any desired size depending on the demands or requirements of a particular operation. Operations have been conducted utilizing tubes of 4 in. diameter and 52 in. in length.

The main coil may be connected to an inlet pipe 9 and to a discharge pipe or line 10 through suitable connections 11 such as suitably conformed return bend units.

As shown more particularly in Fig. 2, the return bend comprises a lower section 12 and an upper section 13. The upper section is molded with the vertical cores 14 which communicate with the horizontal core portion 15. As shown, the upper section may be suitably conformed so as to provide the shoulders 16 upon which the terminal edges of the tubes 7 are supported.

The lower section 12 of the return bend is molded to provide a core portion 17. As will be observed, when the two sections are assembled with the contiguous faces in registry a passageway is provided for the gases from one tube 7 through the return bend and thence to the other tube.

In assembling the unit the sections 12 and 13 may be joined by means of any suitable cement to provide a return bend unit in which the joint 18 lies in a horizontal plane. When the coil is installed in operative position in a furnace the lower return bends are supported directly on the floor of the furnace and the upper return bends are spaced a sufficient distance below the roof to

provide adequate space for unrestricted thermal expansion of the tubes.

It will be observed that in this type of structure the entire weight of the tubes is wholly supported on the floor of the furnace through the lower return bends. Since the seams or joints of the return bends are in a plane normal to the axis of the tubes and to the plane of the compression load any tendency of the seams to open is resisted by the weight of the coil section positioned above such seam. In other words, the weight of a portion or all of the upper return bends and the full weight of the tubes associated with each lower return bend are advantageously utilized to apply pressure to and hence seal the horizontal seam. In the case of the upper return bends, the weight of the upper section acts to oppose any tendency of its seam to open.

It is to be noted also that by disposing the seam of the return bends in a horizontal plane such seams are spaced above the floor and below the roof and hence the entire area of the seam may be reached for inspection and repair. This is in marked contrast to the prior structure in which, as previously noted, a portion of the vertical joint of the lower return bend was contiguous the floor and could not be completely cemented.

The marked efficacy and value of this improved structure can more readily be appreciated and evaluated by consideration of comparative operations utilizing the older type return bend with a vertical seam in one case and the novel structure of the invention in the other.

A test was conducted which exemplified the shortcomings of the older type structure. In this, a continuous coil, of the type described, was constructed of a series of refractory tubes and return bends and was disposed within a furnace. The return bends were made with vertical seams in accordance with earlier practice. Relatively cool air was continuously introduced into the inlet of the coil and during passage therethrough was heated by means of hot combustion gas passing through the furnace in contact with the exterior of the coil. The air was thus raised to a discharge temperature of 2800° F. About one month after commencement of the operation fine cracks appeared in the return bends coincident with the vertical seams. While the loss of air was definite and measurable it was initially slight. However, with continued operation of the furnace these cracks widened or expanded and finally became so large that considerable quantities of air was lost, greatly affecting the control of the process in which the heated air was utilized. The furnace was then shut down and the cracks repaired as far as possible with a refractory cement. However, a certain portion of the cracks contiguous the floor of the furnace could not be reached for cementing. While the leakage through such residual cracks was small it did require a compensating adjustment of the quantity of air admitted to the coil. The furnace was continued in use for several months when the cracks reappeared and leakage became so great as to again require repair. Such recurrent repair involved considerable loss of time in cooling down the furnace, repairing the leaks and reheating to operating temperatures. Considering such loss of time the operating efficiency of the furnace was of the order of 70 to 80%.

Similar tests were conducted employing the continuous coil structure of the present inven-

tion, i. e., a coil composed of vertically positioned refractory tubes and connected return bends the seams or joints of which return bends were in a plane normal to the axis of the tubes. Air was passed continuously through the coil and heated to a discharge temperature of 2300° F. as in the control test. It was found that such coil insured the operation of the furnace for prolonged periods of time because the seams in the return bends did not open to form cracks. It was determined that this improved type of coil permitted operation of the furnace with an efficiency of over 95%.

It will be understood that the particular embodiment of the invention shown and described is chosen to exemplify the essential principle of the invention, namely, of inhibiting leaks in the seams of return bends or equivalent units by disposing such seams in a non-vertical or substantially horizontal plane such that compressive loads of the coil are positively utilized to maintain an unbroken seam or joint. The invention, as will be appreciated, is susceptible of wide permissive variations in construction and specific design of return bend or equivalent units. For example, while the tube units have been shown as connected in series it is apparent that they may be connected in parallel, utilizing a refractory monolith, in the form of a manifold, in lieu of the separate return bends. Such a monolith manifold may be designed and constructed to present a horizontal duct or aperture extending substantially its entire length which duct is in communication with a plurality of refractory tubes. Similarly, it will be appreciated that the return bend seam does not necessarily have to be a truly flat surface; the essential feature of the invention, as noted, is the utilization of a substantial component of the weight of the tube and half the upper return bend to assist in sealing a joint in the lower return bend.

Again, it is apparent that several units may be employed in one furnace, each unit comprising a plurality of tubes in parallel communication with a single upper and single lower monolith manifold, which units may be interconnected either in series or parallel or both. Such monolith units may be fabricated in one piece or in sections such that the seams are a horizontal plane.

While the tubes have been shown disposed in an essentially vertical plane it will be appreciated that they may be positioned at some angle to the vertical; in such case the vertical component of forces operating to prevent opening of the seams would, of course, not be as great where the tubes are vertical but would be of sufficient magnitude to insure improved sealing of the return bends or monoliths.

It will be understood that while the specific example of the operation of the furnace involved the heating of air to a predetermined high temperature this is merely illustrative of the efficiency of the structure. The air heated in the unit may be utilized immediately in any desired high temperature reaction such, for example as described in the copending application referred to, by passing it into a reaction chamber to react with hydrocarbons to produce acetylene. Obviously, instead of air any other gas which does not react

chemically with the refractory material may be heated in the unit for subsequent reaction or other desired purpose. Similarly, it will be understood that this novel unit may be employed as a reaction chamber in processes involving gas or vapor phase reactions at highly elevated temperatures of the range described.

While preferred modifications of the invention have been described it is to be understood that these are given didactically to exemplify the underlying principles involved and not as limiting the useful scope of the invention to the specific illustrative embodiments.

I claim:

- 15 1. An apparatus for heating fluids which comprises, a furnace, a ceramic heating unit positioned within the furnace through which fluids to be heated are passed, the unit comprising a series of return bends of refractory ceramic material supported directly on the floor of the furnace, a series of vertically positioned tubes connected at one end with such return bends and at the other end with a series of refractory return bends, which latter return bends are spaced below the roof of the furnace, the said return bends being comprised of cemented sections, the joint between which lies in a plane substantially normal to the axis of the tubes.
- 20 2. An apparatus for heating fluids comprising, a furnace, a coil positioned within the furnace through which fluids to be heated are passed, said coil comprising a plurality of vertically positioned refractory ceramic tubes, a plurality of interchangeable return bends of refractory ceramic material connected in series with each end of the said tubes to form a continuous coil, the return bends being formed of cemented sections, the joint between which sections lies in a plane substantially normal to the axis of the tubes.
- 25 3. An apparatus for heating fluids which comprises, a furnace, a ceramic heating unit positioned within the furnace through which fluids to be heated are passed, the unit comprising a lower series of return bends of refractory ceramic material supported directly on the floor of the furnace, a series of vertically positioned tubes connected at one end with said return bends and at the upper end with an upper series of refractory return bends, interchangeable with said first return bends, which upper return bends are spaced below the roof of the furnace, the said return bends being comprised of cemented sections, the joint between which sections lies in a plane substantially normal to the axis of the tubes.
- 30 4. An apparatus for heating fluids which comprises, a furnace, a coil positioned within the furnace through which fluids to be heated are passed, said coil comprising a plurality of vertically positioned refractory ceramic tubes, a plurality of interchangeable return bends of refractory ceramic material connected in series with each end of the said tubes to form a continuous coil, the return bends being formed of cemented sections, the joint between which sections lies in a plane substantially normal to the axis of the tubes.
- 35 5. An apparatus for heating fluids which comprises, a furnace, a ceramic heating unit positioned within the furnace through which fluids to be heated are passed, the unit comprising a lower series of return bends of refractory ceramic material supported directly on the floor of the furnace, a series of vertically positioned tubes connected at one end with said return bends and at the upper end with an upper series of refractory return bends, interchangeable with said first return bends, which upper return bends are spaced below the roof of the furnace, the said return bends being comprised of cemented sections, the joint between which sections lies in a plane substantially normal to the axis of the tubes.
- 40 6. An apparatus for heating fluids which comprises, a furnace, a coil positioned within the furnace through which fluids to be heated are passed, said coil comprising a plurality of vertically positioned refractory ceramic tubes, a plurality of interchangeable return bends of refractory ceramic material connected in series with each end of the said tubes to form a continuous coil, the return bends being formed of cemented sections, the joint between which sections lies in a plane substantially normal to the axis of the tubes.
- 45 7. An apparatus for heating fluids which comprises, a furnace, a coil positioned within the furnace through which fluids to be heated are passed, said coil comprising a plurality of vertically positioned refractory ceramic tubes, a plurality of interchangeable return bends of refractory ceramic material connected in series with each end of the said tubes to form a continuous coil, the return bends being formed of cemented sections, the joint between which sections lies in a plane substantially normal to the axis of the tubes.
- 50 8. An apparatus for heating fluids which comprises, a furnace, a coil positioned within the furnace through which fluids to be heated are passed, said coil comprising a plurality of vertically positioned refractory ceramic tubes, a plurality of interchangeable return bends of refractory ceramic material connected in series with each end of the said tubes to form a continuous coil, the return bends being formed of cemented sections, the joint between which sections lies in a plane substantially normal to the axis of the tubes.
- 55 9. An apparatus for heating fluids which comprises, a furnace, a coil positioned within the furnace through which fluids to be heated are passed, said coil comprising a plurality of vertically positioned refractory ceramic tubes, a plurality of interchangeable return bends of refractory ceramic material connected in series with each end of the said tubes to form a continuous coil, the return bends being formed of cemented sections, the joint between which sections lies in a plane substantially normal to the axis of the tubes.
